United States of America as represented by the Secretary
of the Army

Filed Nov. 30, 1960, Ser. No. 72,816

10 Claims. (Cl. 343—713)

(Granted under Title 35, U.S. Code (1952), sec. 266)

The invention described herein may be manufactured and used by or for the Government for governmental purposes, without payment of any royalty thereon.

The present invention relates to an improved broad-band vertical antenna and more particularly to one for vehicular application constructed in the form of a whip and employing a double feed system, facilitating its use over a broad band of frequencies.

In the prior art, whip antennas for vehicular use required complicated circuitry and were not conveniently adjustable for operation over a wide frequency range. The present invention is a vertical whip antenna (operating, for example, over the frequency range from 20 to 76 mc.) which will permit considerable simplification of the antenna circuitry of vehicular radio sets, especially with respect to simplification of the matching circuitry of the radio sets, and which will also permit an increase in antenna efficiency.

The present invention is an improvement over my Patent No. 2,913,722. The antenna system described therein comprises an antenna having upper and lower sections, a cable choke connected to the base of the lower section, reactance circuits, and switching means for connecting the reactance circuits to the upper and lower sections. The invention herein provides improvements over the above-mentioned patent by having the cable choke wound around a ferrite core to reduce the turns required, and by having a tapped shunt coil connected across the cable choke to minimize the ferrite losses at high frequencies. In addition, the upper section has now been changed to provide a dual function. While it still behaves as an upper radiator, it also acts as an impedance matching stub, being either open-ended or shorted, depending on the load impedance. This latter structural change results in the voltage standing wave ratio (VSWR) of the antenna being reduced. Another means for reducing the VSWR is the introduction of a taper in the lower section so that a portion thereof will have a relatively high characteristic impedance, the remainder of the lower section having a somewhat lower characteristic impedance.

Principal Advantages

(1) The proven mechanical advantages of the whip configuration are not compromised. There are no moving parts, telescoping sections, or lumped reactors in the whip itself.

(2) The length of the cable choke is kept to a minimum by having it wrapped around a ferrite core. A tapped shunt coil is connected in parallel with the cable choke to decrease the inductance as the frequency is increased and to minimize the ferrite losses at high frequencies.

(3) The problem of matching the antenna to the utilization device (either a receiver or transmitter) over the entire frequency range is solved by the use of a variable lumped-reactor comprising the cable choke wound on the ferrite core, the tapped coil shunting the choke, the impedance matching networks, and the switching means. By switching to the proper impedance matching network and to the proper tap on the tapped coil, by means of an automatic remote control activated by the

2

frequency dial of the utilization device, the frequency range is divided into a number of fairly wide bands, each band having the proper reactance value. This permits controlling the current distribution along the lower section of the antenna below the feed point within wide limits so that a current node is placed at or near the lower end of the lower section in all bands. As a result, the distortion of the azimuth pattern and the loss caused by unintentional excitation of the vehicle body are minimized. Most important, the decoupling between antenna and vehicle body actually achieved is sufficient to make differences in impedance due to vehicle type, mounting location and ground conditions negligibly small. As a secondary effect, the power gain with respect to the field strength on the ground is improved noticeably at the upper end of the frequency range. In addition, the feed cable from the antenna to the utilization device can be any arbitrary length, no tuning is involved, and the voltage standing wave ratio (VSWR) is kept small over the entire frequency range.

(4) To reduce the VSWR in adjoining sections of the antenna, over the entire frequency range, the upper section of the antenna is constructed so that its acts as a radiator and stub simultaneously, and the lower section 25 of the antenna is constructed with a tapered portion. The tapering of the lower section has an additional advantage of equalizing the antenna impedance seen at the lower end of the cable choke and the characteristic impedance of the transmission line connected to the utilization device.

30 The advantages of lower VSWR are lower line loss, and lower voltage across the transmission line and other components (less danger of voltage breakdown). Also, lower VSWR permits use of simpler, less "lossy" matching networks. The same advantage accrues from equalizing the impedance seen at the lower end of the cable choke and the characteristic impedance of the transmission line connected to the utilization device, which may be a transmitter or a receiver.

35 The exact nature of this invention as well as its many other advantages will be readily apparent from consideration of the following specification relating to the annexed drawings in which:

40 FIGURE 1 is a schematic illustration of the invention; and

45 FIGURES 2A and 2B are enlarged views of alternative connections of the upper radiator (stub) to the lower radiator.

50 Although the antenna may be used with either receiving or transmitting equipment, it will be referred to, for convenience, as a radiator, as for a transmitter. Therefore, the terms upper radiator and lower radiator are used throughout the specification and claims as generic to both transmitting and receiving antennas. The terms section and radiator applied to the antenna elements, as upper section or upper radiator 12, are equivalent. Also, the term utilization device, as used herein, is to be considered generic to transmitters and receivers.

55 Referring now to the drawings, wherein like reference characters designate like or corresponding parts throughout the several views, there is shown in FIGURE 1, an improved double feed whip antenna system comprising an upper section (upper radiator) 12 and lower section (lower radiator) 13, the two sections 12 and 13 being inclosed within an insulating jacket 14. In a preferred embodiment the antenna is 122 inches in length with the upper radiator 12 being approximately 69 inches and the lower radiator 13 being approximately 53 inches. Insulating jacket 14 serves to support and stiffen the coaxial conductors 12 and 13. This jacket may be of fiberglass or similar high-strength insulating material.

Spring 45 and base insulator 49, each coaxial with lower section 13 at its bottom end are positioned outside of and adjacent to insulating jacket 14, as shown, and act as the base support for the antenna. Base insulator 49 is attached to vehicle body member 48 where the lower section 13 passes through that member to connect to cable choke 17.

A shield housing 52 is mounted within vehicle body member 48 about base insulator 49. Encased within this housing is ferrite-cored cable choke 17, tapped shunt coil 60 (shunting the cable choke), impedance matching networks, and ganged switching network 20.

Ganged switching network 20, remotely controlled from the radio set or other utilization device 61, and activated automatically from a band selector (not shown), is illustrated as comprising five ganged switches 23, 24, 25, 26 and 27—each having a switch arm and three switch positions I, II and III. This switch permits changing the impedance of the network (matching networks 36, 39 and 41, cable choke 17, and tapped shunt coil 60) coupling the antenna to utilization device 61 by inner conductor 43 of coaxial cable 44, as described more fully in my Patent No. 2,913,722.

While each deck of ganged switching network 20 is shown having three positions for covering the entire frequency range, a greater number of such positions and impedance matching networks may be used. Tapped shunt coil 60 will accordingly have an additional number of taps.

The lumped reactor at the base of lower radiator 13 has, an essential component, a section of coaxial cable wound on ferrite core 59 to form cable choke 17, the ferrite core being used to keep the number of turns of the cable choke to a minimum.

For the purpose of illustration, cable choke 17 is shown as having one turn in FIGURE 1. Actually, however, it will have a plurality of turns. Because of the ferrite core the preferred embodiment needs only four and one-half turns of cable (twenty-three inches of cable length) to obtain an inductance of 2 μ h. The ferrite core in this embodiment is a cylinder 1.0 inch in diameter and 2.0 inches long.

Connector 62 couples one end of cable choke 17 to the base of lower radiator 13. If desired, the cable choke can be formed integral with the lower radiator. At the other end of the cable choke the inner conductor is connected to switching network 20, and the outer-conductor is grounded to housing 52 which shields network 20.

Tapped shunt coil 60, a cylindrical air-core coil, with relatively loose coupling between turns, is connected in parallel with cable choke 17. The taps are each connected to a switch terminal of switch deck 24 to permit adjustment of the coil, according to the switch position, to tune the selfcapacitance of the cable choke and the capacity of the base insulator and other associated hardware to enhance the broad-band properties of the antenna. Adjustment of the inductance value of this coil, by the use of the taps, is preferable to an adjustment of the cable choke, particularly in the higher frequency range to minimize the ferrite losses of core 59. As the frequency is increased the inductance of the shunt coil is lowered in steps, and a larger portion of the circulating currents due to the capacity of the base assembly flows through it rather than through the cable choke. As a result the losses in the base reactor assembly, using a ferrite core such as that commonly known as Q-2, do not exceed 5% of the antenna input power.

The criterion used in adjusting the taps of the shunt coil is primarily the position of the node of the current distribution along the antenna. Specifically, positioning the node at the base minimizes its coupling to the vehicle body, whereas positioning the (virtual) current node below the base of the antenna, corresponding to a capacitive susceptance of the base reactor, greatly alleviates

the difficulty of matching at the lower end of the frequency range.

Upper section 12 of the antenna comprises a coaxial line having outer conductor 12a and inner conductor 12b. This line acts as a radiator for currents flowing on the outside of outer conductor 12a, and as a stub for currents flowing on the inside of outer conductor 12a and in inner conductor 12b (currents in 12b are always equal in magnitude and opposite in direction to those on the inside of outer conductor 12a). The arrows in FIGURES 2A and 2B show the current flow for a series-connected stub and parallel-connected stub, respectively. The dashed capacitors in these figures depict the capacitance between the cable portions closing the antenna circuit.

When inner conductor 12b is shorted to outer conductor 12a (FIGURE 2B), the line acts as a shorted stub. With this type of termination, the center conductor 12b is usually connected in parallel with the feed-point impedance of the antenna (see FIGURE 2B) although in narrow-band applications the series connection might be employed to advantage.

Upper radiator 12 may also be open-ended, as in FIGURE 2A, wherein the length of the inner conductor is the length of the stub and the length of the outer conductor is equal to or greater than the stub length. In this arrangement upper radiator 12 is connected usually in series with lower radiator 13.

The embodiments shown in FIGURES 2A and 2B are not equivalent, but are complementary. The series connection of the stub (usually resonant in the middle of the frequency range) is most effective with respect to broadband compensation when the load impedance (in this case the feed point impedance) is high. On the other hand, the parallel connection is useful when the load impedance is low.

Lower section 13 is formed of two transmission lines 63 and 64 of different diameter and characteristic impedance. The lower end of 63 is tapered to match the smaller diameter of 64, as shown in FIG. 1.

The tapering of the line made up of 63 and 64 has the effect of equalizing the antenna impedance seen at 35 to that of the characteristic impedance of coaxial cable 44. Any tapering, gradual or in steps, can be done to the inner conductor alone, to the outer conductor alone, or to both.

The stub 12 and the tapered section made up of 63 and 64 can be used either together or independently of each other to reduce the VSWR over the entire frequency range. The advantages of lower VSWR are lower line-loss and lower voltage (less danger of voltage breakdown). Also, low VSWR permits the use of simple, less lossy impedance matching networks 36, 39, 41, etc.

It should be understood, of course, that the foregoing disclosure relates to only a preferred embodiment of the invention and that numerous modifications or alterations may be made therein without departing from the spirit and scope of the invention as set forth in the appended claims.

What is claimed is:

- An improved broad-band whip antenna for vehicular use comprising: an antenna having an upper section and a lower section electrically coupled to said upper section; a ferrite core; a cable choke wound around said ferrite core; means for connecting said lower section to said cable choke; a tapped shunt coil connected in parallel with said cable choke and having a plurality of taps; a plurality of impedance matching networks; and switching means for connecting any one of said impedance matching networks to said antenna and for changing the inductance of said shunt coil by the tap setting according to the frequency band at which the antenna is to operate.

2. The improved broad-band whip antenna of claim 1 wherein said lower section is formed of two coaxial lines, one line having a lower characteristic impedance

than the other, the line of lower characteristic impedance being connected to said cable choke, said line with the higher characteristic impedance having a tapered end connected to said line with the lower characteristic impedance.

3. The improved broad-band whip antenna of claim 2 wherein said cable choke is formed of a coaxial cable, the inner conductor of which has its ends connected to said switching means and to the inner conductor of said lower section, respectively.

4. The improved broad-band whip antenna of claim 3 wherein said upper section is formed of a coaxial line having the upper extremity of the inner conductor insulated from the outer conductor and the lower extremity of the inner conductor connected to said inner conductor of said lower section.

5. The improved broad-band whip antenna of claim 3 wherein said upper section is formed of a coaxial line with the inner conductor connected to the outer conductor of said lower section and the outer conductor connected to the inner conductor of said lower section.

6. An antenna system for vehicular use comprising: an antenna insulated from and projecting outwardly from the structure of the vehicle so as to be electrically exposed to space, said antenna having upper and lower sections; an insulating jacket enclosing said antenna; a ferrite core; a cable choke wound around said ferrite core and connected to the lower extremity of said lower section; a tapped shunt coil having a plurality of taps and its extremities connected in parallel with said cable choke; a plurality of impedance matching networks; a switching means for interconnecting said impedance matching networks to said antenna and for changing the tap connections on said tapped shunt coil.

7. An improved broad-band whip antenna system for vehicular use comprising: an upper section formed of a coaxial line; a lower section having an upper and lower portion, each portion being formed of a coaxial line, the lower end of said upper portion being tapered and butt-connected to the upper end of said lower portion; section connection means for connecting said lower section to said upper section; an insulating jacket enclosing said upper and lower sections; a ferrite core; a cable choke of coaxial cable wound around said ferrite core; means for connecting said cable choke to said lower section; a tapped shunting coil having a plurality of taps, said shunting coil connected in parallel with said cable choke across the outer conductor of said coaxial cable forming said cable choke; a plurality of impedance matching networks; a utilization device; and a switching means for interconnecting said impedance matching networks between said antenna and said utilization device and for changing the in-

ductance of said shunt coil by the tap setting according to the frequency band at which the antenna is to operate.

8. An improved broad-band whip antenna system for vehicular use comprising: an upper radiating section formed of a coaxial line; a lower radiating section having an upper and a lower portion, each portion being formed of a coaxial line, said upper portion having a higher characteristic impedance than said lower portion, said upper portion having its lowest extremity tapered, said lower portion having its upper extremity connected to said tapered extremity of said portion; section connection means for connecting said upper section to said lower section; an insulating jacket enclosing and supporting said upper and lower sections; a ferrite core; a cable choke of a coaxial cable wound around said ferrite core; a switching means; means for connecting the inner and outer conductors of one end of said cable choke to the inner and outer conductor, respectively, of said lower portion of said lower section, the inner and outer conductors of the other end of said cable choke being connected to said switching means and ground, respectively, said outer conductor of said one end of said cable choke being connected to said switching means; a tapped shunt coil having a plurality of taps and connected to the outer conductor of said cable choke in parallel therewith, said taps being connected to said switching means; a utilization device; and means for connecting said utilization device to said switching means; whereby said switching means connects one of said plurality of impedance matching networks between said antenna and said utilization device and changes the inductance of said shunt coil by the tap setting according to the frequency band at which the antenna will operate.

9. The improved broad-band whip antenna system of claim 8 wherein the inner conductor of said upper section is connected to the outer conductor of said lower section and said outer conductor of said upper section is connected to said inner conductor of said lower section to form said section connection means, so that said upper section acts as a radiator and parallel connected stub simultaneously.

10. The improved broad-band whip antenna system of claim 8 wherein the lower extremity of the inner conductor of said upper section is connected directly to the inner conductor of said lower section to form said section connection means, so that said upper section acts as a radiator and a series-connected stub simultaneously.
